UNITED STATES PATENT OFFICE.

ALFRED A. BECKER, OF LAKEWOOD, OHIO, ASSIGNOR TO THE GEORGE H. BOWMAN COMPANY, OF CLEVELAND, OHIO, A CORPORATION OF OHIO.

Application filed December 10, 1923, Serial No. 679,645.

This invention relates to wagons and more particularly, to metal wagons of a size suitable for use by children. Two of the chief requirements of wagons of this character are that they be of pleasing appearance and extremely strong and durable so that they will successfully withstand the rough usage to which they are subjected by children; and second, the parts thereof must be capable of production and assembly at relatively low cost.

The object of the present invention, therefore, is to provide an improved wagon of this character which successfully meets the above and other requirements, some of the features of the present wagon being the following:

The wagon platform and the body band with its upper tubular edge portion are formed in one piece, with the result that it is unnecessary to provide these members with attaching means and to provide the platform with strengthening tubular side portions as heretofore. The construction of these parts is therefore not only simplified and a stronger and more rigid structure provided, but the possibility of the body band becoming loose or detached and lost is also precluded.

The supporting means for the rear axle is a unitary bracket stamped from sheet metal, the end portions of which are bent to provide re-enforcing side flanges and the intermediate portion near each end thereof is formed with downwardly extending arms, the lower end portions of which are rolled into substantially tubular form to embrace the rear axle. At the top of each of the side and intermediate portions a laterally extending flange is formed for securing the bracket to the wagon platform. The intermediate portion near each end thereof is also formed with vertically disposed ribs extending down into the arms thereof and forming a part of the axle embracing portions, said ribs materially strengthening the bracket against bending and other strains.

The front axle structure also comprises a unitary sheet metal bracket having a central body portion from which extend two downwardly and outwardly curved arms, the lower ends of which are rolled into substantially tubular form to embrace the front

axle. The central body portion is provided at its top and bottom with rearwardly extending flanges, through which the king pin extends, the upper end of said pin seating in the recessed portion of a metal strip secured to the wagon platform. The bottom of the bracket is steadied and braced by a metal stand, the rough usage to which they are subjected by children; and second, the parts thereof must be capable of production and assembly at relatively low cost.

The object of the present invention, therefore, is to provide an improved wagon of this character which successfully meets the above and other requirements, some of the features of the present wagon being the following:

The wagon platform and the body band with its upper tubular edge portion are formed in one piece, with the result that it is unnecessary to provide these members with attaching means and to provide the platform with strengthening tubular side portions as heretofore. The construction of these parts is therefore not only simplified and a stronger and more rigid structure provided, but the possibility of the body band becoming loose or detached and lost is also precluded.

The supporting means for the rear axle is a unitary bracket stamped from sheet metal, the end portions of which are bent to provide re-enforcing side flanges and the intermediate portion near each end thereof is formed with downwardly extending arms, the lower end portions of which are rolled into substantially tubular form to embrace the rear axle. At the top of each of the side and intermediate portions a laterally extending flange is formed for securing the bracket to the wagon platform. The intermediate portion near each end thereof is also formed with vertically disposed ribs extending down into the arms thereof and forming a part of the axle embracing portions, said ribs materially strengthening the bracket against bending and other strains.

The front axle structure also comprises a unitary sheet metal bracket having a central body portion from which extend two downwardly and outwardly curved arms, the lower ends of which are rolled into substantially tubular form to embrace the front

axle. The central body portion is provided at its top and bottom with rearwardly extending flanges, through which the king pin extends, the upper end of said pin seating in the recessed portion of a metal strip secured to the wagon platform. The bottom of the bracket is steadied and braced by a metal stand, the rough usage to which they are subjected by children; and second, the parts thereof must be capable of production and assembly at relatively low cost.

The object of the present invention, therefore, is to provide an improved wagon of this character which successfully meets the above and other requirements, some of the features of the present wagon being the following:

of the wagon. The upper edge portion of the body band is rolled outwardly into substantially tubular form, as at 7, which not only provides smooth rod-like hand grips around the entire upper edge portion of the body band but also thoroughly reinforces the body band against bending strains. If desired, the upper edge portion of the body band may be rolled around a strengthening rod, but in any event, will be of sufficient size to preclude the possibility of injury by cutting.

The rear axle 4 is carried by a unitary bracket, stamped from sheet metal, the triangular end portions of which are bent forwardly at substantially ninety degrees to the intermediate portion 8 to provide re-enforcing side flanges 9. Preferably, each of said side flanges is provided with a centrally disposed, triangular cut-out portion 10 to improve the appearance of the bracket.

The intermediate portion 8 is provided near each end thereof with a downwardly extending arm 11, the lower end of which is rolled into substantially tubular form to provide spaced, axle embracing portions 12. A vertically disposed, rearwardly extending rib or ridge 13 is formed in each end portion of the intermediate portion 8, said ribs extending down into the arms 11 thereof and forming a part of the axle embracing portions 12, as clearly shown in Fig. 4, with the result that the bracket is materially strengthened against bending strains. The lower curved edge portion of the intermediate portion 8 between the axle embracing portions 12 thereof is bent forwardly, as at 14, which not only strengthens the bracket but also improves its appearance when viewed from the rear.

The re-enforcing side flanges 9 are each provided with an inwardly extending top flange 15 and the intermediate portion 8 is provided with a forwardly extending top flange 16, flanges 15, 16 being adapted to be secured to the under surface of the wagon platform 1 by any suitable means, bolts 17 being here shown. In order to prevent overlapping of these securing flanges, the adjacent corner portions thereof are cut away, so that the edges of adjacent flanges just meet, thereby providing a stronger structure and improving its appearance when viewed from below.

The front axle structure also comprises a unitary sheet metal bracket having a central body portion 18 from which extend two downwardly and outwardly curved arms 19, the lower ends of which are rolled into substantially tubular form to provide spaced axle embracing portions 20. The upper and lower edge portions of said arms are bent rearwardly, as at 21, to not only strengthen the bracket but to present a more pleasing appearance when viewed from the front.

Each of the arms of said bracket is provided with a vertically disposed, forwardly extending strengthening rib 22, said ribs extending down and forming a part of the axle embracing portions 20 thereof.

At the bottom of the central body portion 18 of said bracket is a rearwardly extending flange 23, while at the top of said body is an upwardly extending rectangular portion 24, at the upper end of which is a rearwardly extending flange 25, said flange being in vertical alignment with the bottom flange 23.

Extending through the front end portions of flanges 23 and 25 at substantially the middle points thereof is a king pin 26, the upper headed end of which is adapted to seat in the centrally disposed, recessed portion 27 of a metal strip 28, transversely disposed with respect to the wagon platform 1 and having its end portions suitably secured to the lower surface thereof, such as by the bolts 29. The bottom portion of the front axle bracket is steadied and braced by a metal strip 30 having its front end surrounding the king pin 26 and interposed between the lower headed end of said pin and the lower bracket flange 23. The rear end of said bracing strip is suitably secured to the lower surface of the platform 1 at substantially the middle point thereof, such as by the bolt 31.

The wagon hounds comprise a unitary substantially stirrup-shaped metal strip embracing the upwardly extending rectangular portion 24 of the front axle bracket. The intermediate portion 32 of the hounds is secured, such as by the rivets 33, to the rear face of said bracket portion 24 just below the rearwardly extending upper flange 25 thereof, said intermediate portion 32 being provided with a centrally disposed, vertically extending recess or channel 34 for the reception of the king pin 26 which is interposed between the central portion of the bracket and the intermediate portion of the hounds. With this arrangement, a pull applied to the hounds is exerted against the king pin and to the metal strips 30 and 28 secured to the wagon platform, and not to the front axle bracket alone.

Pivotedly mounted on the pin 35 extending through the front end portions of the arms 36 of the hounds is the wagon handle 37, of wood or other suitable material, having the usual cross pin 38 at its upper end.

The front wheels 5 and rear wheels 6 of the wagon are of like construction and in the embodiment here shown are of the disk type. Each of said wheels comprises two dished side plate members 39, stamped from sheet metal, each of said members being provided with a laterally extending, annular marginal flange 40. Each member is also provided with a centrally disposed axle

opening 41, the metal around said openings being bent inwardly, as at 42, to provide increased bearing surface for the axles.

The wheel is assembled by pressing the two members together with the flange of the outer member enclosing the flange of the inner member and then beading the flange of the outer member thereover, as clearly indicated in Fig. 8. The wheels are held on the axles by any suitable means, cotter pins 43 being here shown, washers 44 being provided on each side of each wheel, as is usual.

What I claim is:

- 15 1. An axle bracket structure for toy wagons, comprising a unitary sheet metal member having the end portions thereof bent at substantially ninety degrees to the intermediate portion to provide re-enforcing side flanges, said intermediate portion being provided with spaced axle receiving portions, thereby providing a strong and ornamental structure.
- 25 2. An axle bracket structure for toy wagons, comprising a unitary sheet metal member having the end portions thereof bent at substantially ninety degrees to the intermediate portion to provide re-enforcing side flanges, said intermediate portion being provided with spaced axle receiving portions, said intermediate and side flange portions being provided with laterally extending securing flanges.
- 35 3. A front axle structure for toy wagons, comprising a unitary sheet metal bracket having a central body portion and end axle

receiving portions, said body portion being provided with upper and lower rearwardly extending flanges, a king pin extending through the upper flange, and hounds secured to said body portion between said upper and lower flanges. 40

4. A front axle structure for toy wagons, comprising a unitary sheet metal bracket having a central body portion and end axle 45 receiving portions, said body portion being provided with upper and lower rearwardly extending flanges, a king pin extending through said flanges, and hounds in the form of a unitary metal strip embracing said body 50 portion and said king pin and secured to the former.

5. A front axle structure for toy wagons, comprising a unitary sheet metal bracket having a central body portion and end axle 55 receiving portions, said body portion being provided with upper and lower rearwardly extending flanges, a king pin extending through said flanges, the upper end of said king pin being adapted to be secured to the wagon platform, hounds embracing said body portion and the king pin and secured to the former, and a metal bracing strip having one end portion surrounding said 60 king pin and interposed between the lower end of said pin and the lower bracket flange, the other end portion of said bracing strip being adapted to be secured to the wagon platform. 65

In testimony whereof I hereby affix my 70 signature.

ALFRED A. BECKER.
